UNITED STATES PATENT OFFICE

163,324

PORTABLE ELECTRIC TOOL

Charles Rittenhouse, Cincinnati, Ohio

Application February 28, 1950, Serial No. 8,207

Term of patent 14 years

(Cl. D54—14)

To all whom it may concern:

Be it known that I, Charles Rittenhouse, a citizen of the United States, residing at Cincinnati, in the county of Hamilton, and State of Ohio, have invented a new, original, and ornamental Design for a Portable Electric Tool, of which the following is a specification, reference being had to the accompanying drawing forming part thereof, in which:

Fig. 1 is a plan view of the portable electric tool showing my new design.

Fig. 2 is a side view of the same.

Fig. 3 is a front view of the same.

I claim:

The ornamental design for a portable electric tool, substantially as shown.

CHARLES RITTENHOUSE.
